UNITED STATES PATENT OFFICE

WALTER C. ANDERSON, OF GLEN ROCK, NEW JERSEY, ASSIGNOR TO BRANDS LABORATORIES, INC., OF NEWARK, NEW JERSEY, A CORPORATION OF NEW JERSEY

ELECTROMAGNETIC SOUND-REPRODUCING APPARATUS

Application filed June 12, 1928. Serial No. 284,773.

My invention relates broadly to electromagnetic sound reproducers and more particularly to a sound reproducer of the conical diaphragm type.

One of the objects of my invention is to provide a construction of electromagnetic sound reproducer which is capable of manufacture and production on a mass production scale having a minimum number of parts which may be assembled with a minimum degree of skill for efficient operation in the reproduction of sound over a broad frequency range. Another object of my invention is to provide a practical construction of sound reproducer wherein an electromagnetic operating mechanism may be suspended within a chassis and all parts of the electromagnetic sound reproducer supported by the chassis, thereby forming a compact assembly of the sound reproducer.

A further object of my invention is to provide a chassis construction for a loud speaker wherein a conical shaped diaphragm may be supported by a chassis in a position to be driven from the electromagnetic operating mechanism carried in the chassis for providing a compact assembly of electromagnetic sound reproducer particularly adapted for mounting within a cabinet structure.

Still another object of my invention is to provide a construction of electromagnetic sound reproducer, wherein a pivoted armature member is assembled within an electromagnetic driving system and between pairs of inwardly directed pole faces with a bridging member extending over the electromagnetic operating mechanism and carrying means for transferring vibrations from the pivoted armature to a conical shaped sound reproducing diaphragm.

Other and further objects of my invention reside in the construction of parts for an electromagnetic sound reproducer described more fully hereinafter by reference to the accompanying drawings, in which:

Figure 1 is an elevational view looking at the back of the sound reproducer and showing the electromagnetic operating mechanism mounted in position on the chassis for driving the conical shaped sound reproducing

diaphragm; Fig. 2 is a side elevation of the assembled electromagnetic sound reproducer; Fig. 3 is a lateral cross-sectional view of the electromagnetic sound reproducer illustrated in Fig. 2; Fig. 4 is a longitudinal cross-sectional view taken through the electromagnetic sound reproducer; Fig. 5 is a perspective view of the bridging member employed for the vibration transfer element between the pivoted armature and the sound reproducing diaphragm of the loud speaker; Fig. 6 is a rear perspective view of the chassis forming the support for the elements of the sound reproducer; Fig. 7 is a front perspective view of the chassis which supports the parts of the electromagnetic sound reproducing system; and Fig. 8 is a lateral cross-sectional view taken through the chassis illustrated in Figs. 6 and 7.

In my application Serial No. 179,026, filed March 28, 1927, I have shown a construction of pivoted armature electromagnetic sound reproducer over which the present construction of sound reproducer is a substantial improvement. By my present design of sound reproducer, I provide a unitary means for mounting all of the parts of the sound reproducer by means of a chassis which may be anchored to a base structure and which is particularly adapted for mounting within a cabinet. A cast chassis substantially in the form of a box-like frame is provided, which chassis terminates in a ring shaped portion providing a support for a plurality of radial arms which carry a rim structure from which the conical shaped sound reproducing diaphragm is flexibly suspended. The electromagnetic operating mechanism is mounted upon the chassis and a connection extends from a vibratory armature member to the apex of a conical shaped sound reproducing diaphragm, which projects through the ring shaped extremity of the chassis. The electromagnetic operating mechanism is bridged by a device from which the vibration transfer member is suspended. The parts of the operating mechanism and the sound reproducing diaphragm are compactly assembled with respect to the chassis of the loud speaker structure.

Referring to the drawings in more detail, reference character 1 designates a base on which a chassis 2 is mounted. The chassis includes a pair of side plate portions 3 and a front plate portion 4 terminating in a ring shaped portion 5. The front plate portion 4 is strengthened by means of a rib 40. The side plates 30 terminate in supporting ledges 20 having intermediate cut away portions 20^a. The ring shaped terminus of the front plate 4 is provided with a hub portion 41 which has flattened areas 6 at diametrically opposite points around the periphery thereof which provide connection means for the radiating arms 8 of the frame for the conical shaped sound reproducing diaphragm. A pair of rim members 9 and 10 secured by means of rivets 42 are supported by means of the arms 8. Rims 9 and 10 are substantially channel shaped, thus providing means for supporting the annular pad 11 which may be forced against the rear of a panel which forms the front of a cabinet structure. A flexible annular membrane 43 is secured between the rim members 9 and 10 and connects to the peripheral edge of the cone shaped sound reproducing diaphragm 7. To provide sufficient damping of the sound reproducing diaphragm, I employ an annular strip 12 surrounding a portion of the diaphragm as set forth more fully in copending application Serial No. 172,767 filed by Ralph L. Brown, March 4, 1927. The electromagnetic operating mechanism includes a pair of permanent magnets shown at 15 which are secured on opposite sides of a pair of pole pieces 21 and 22 supported by means of bolt members 17 on angle members 16, which are in turn supported on the ledges 20 of the side plates 3 and secured in position by means of screws 45 as shown. The pole pieces 21 and 22 which are directed toward each other are cut away in the form of pockets 23 and 24 at their adjacent ends, thereby forming sets of pole faces 23^a—24^a and 23^b—24^b. The pockets 23 and 24 provide housings for bobbins 25 and 26, each of which carry electromagnetic windings. The ends of the bobbins extend laterally in the form of flat parallel plates indicated at 29 and 30, and between these end plates there is supported a resilient plate member 28 in which the armature member 31 is centrally positioned, the armature member being free to vibrate in a rocking movement in plate 28 under the influence of the variable magnetic field from bobbins 25 and 26. The assembly of the electromagnetic windings is carried by the parallel extending bar members 33 which form an integral part of a single yoke shaped casting represented at 32 for bridging the pole members 21 and 22. The bridging member has the yoke portion thereof 32 adjacent one end of the parallel extending bars 33 so that the assembly of the electromag-

netic operating mechanism may be supported on plates 30 and 29 by means of screw members 46 which pass into screw threaded apertures in bars 33. The top of the yoke 32 is flattened as represented at 34 to provide a support for the vibration transfer member 35 which depends downwardly from the flattened portion 34. The vibration transfer member 35 has a connecting rod 47 extending from its lower extremity for the transfer of vibrations from armature 31 to the member 35 and then to the sound reproducing diaphragm 7 through the medium of link 36, bushing 37 and the apex piece 38. In order to improve the tone quality of the circuit, provision is made for the mounting of the frame of a choke coil as represented at 49 on one of the side plates 3 by suitable securing means such as screw devices 50. A suitable terminal plate 48 may be mounted on the extremity of one of the side plates bridging the gap 20^a between the ledges 20. A suitable condenser may be mounted adjacent the choke coil and supported from the chassis with flexible connections brought out from the choke coil and condenser circuit and from the circuits of the electromagnetic windings for conveying the operating currents from the output system of an amplifier to the electromagnetic operating mechanism.

The loud speaker construction of my invention has been found to be extremely practical in its construction and successful in its operation.

While I have described particular embodiments of my invention, I desire that it be understood that modifications may be made and that no limitations are intended other than are imposed by the scope of the appended claims.

What I claim and desire to secure by Letters Patent of the United States is as follows:

1. A loud speaker comprising a sound reproducing diaphragm, a pair of permanent magnets, pole pieces positioned therebetween and directed toward each other, an armature located between said pole pieces, an electromagnetic system disposed between said pole pieces, a bridging member having a central portion extending laterally of said pole pieces and offset therefrom and having side portions extending parallel to said pole pieces and connected to said pole pieces and a vibration transmitting means supported by said bridging member and connected with the central portion of said armature for impressing vibrations upon said sound reproducing diaphragm.
2. In a loud speaker system a chassis including a pair of supporting side portions, an electromagnetic driving system disposed between the side portions of said chassis, a ring shaped member carried by said chassis, a conical shaped sound reproducing diaphragm, a frame supporting said diaphragm

and connecting means extending from said ring shaped member to said frame for maintaining said frame in predetermined relation to said chassis, and means connecting said diaphragm with said electromagnetic driving system.

3. In a loud speaker construction a chassis terminating in a substantially circular member adjacent one side thereof, an electromagnetic driving mechanism supported by said chassis, a frame for supporting a sound reproducing diaphragm and radiating arm members extending from said frame and connected to said member for maintaining a predetermined relation between said electromagnetic driving mechanism and said sound reproducing diaphragm.

4. In a loud speaker construction a chassis terminating at one side thereof in a ring shaped member, an electromagnetic driver supported on said chassis, a conical shaped sound reproducing diaphragm having the apex portion thereof projecting through said ring shaped member and connected to said electromagnetic driver, and means extending from said ring shaped member to the outer periphery of said diaphragm for centering said diaphragm with respect to said ring shaped member.

5. A loud speaker comprising a chassis, a pair of angle members supported by said chassis, an electromagnetic operating mechanism carried between said angle members, a sound reproducing diaphragm, means substantially encircling said electromagnetic operating mechanism in a plane offset from one side thereof for supporting said sound reproducing diaphragm from said chassis, and connecting means between said electromagnetic operating mechanism and said sound reproducing diaphragm.

6. A loud speaker comprising a chassis, an electromagnetic operating mechanism carried by said chassis, a conical shaped sound reproducing diaphragm supported from said chassis and connected to said electromagnetic operating mechanism, said chassis including a pair of vertically extending side plate members terminating in parallel extending ledges on the top thereof, and an encircling portion through which the apex of said conical shaped sound reproducing diaphragm extends for connection to said electromagnetic operating mechanism.

7. In a loud speaker construction a chassis for supporting the parts of the loud speaker comprising a pair of vertically extending side members terminating in parallel extending ledges, a vertical plate member extending above the parallel extending ledges of said chassis, a conical shaped sound reproducing diaphragm, a frame supporting said diaphragm, connections between said frame and said chassis, an electromagnetic operating mechanism supported on the ledges of said

chassis, said sound reproducing diaphragm having its apex extending through a portion of said vertical plate member and connected to said electromagnetic operating mechanism.

8. In a loud speaker, a supporting chassis comprising a vertically extending frame, an electromagnetic operating mechanism supported on the extremity of said frame, a conical shaped sound reproducing diaphragm, means supporting said conical shaped sound reproducing diaphragm comprising a rim, a curved frame on said chassis located in a plane offset from one side of said electromagnetic operating mechanism, and a plurality of arms extending between said rim and said curved frame, said diaphragm having its apex protruding through an aperture in said curved frame and connected to said electromagnetic operating mechanism.

9. A loud speaker comprising a frame structure, a pair of pole pieces supported by said frame structure and directed toward each other, a plurality of electromagnetic windings housed by said pole pieces with pole faces extending to positions adjacent each other on opposite sides of said electromagnetic windings, an armature member pivotally mounted within said electromagnetic windings, a conical shaped sound reproducing diaphragm supported from said frame structure, means extending laterally of said pole pieces and connected at each end with said pole pieces, said means having a central offset portion, a vibration transfer member connected at one end with the central offset portion of said means and at the other end with said armature member, and a connection between said member and said diaphragm.

10. A loud speaker comprising an electromagnetic operating mechanism comprising a pair of pole pieces directed toward each other, pockets formed in each of said pole faces, electromagnetic windings disposed in said pockets, an armature member rockable within said electromagnetic windings, a yoke member laterally bridging said pole pieces, a member depending from said yoke, a connection between said rockable armature and one end of said member, a conical shaped sound reproducing diaphragm, and a connection between the apex of said diaphragm and said depending member, whereby vibrations of said rockable armature are communicated to said sound reproducing diaphragm.

In testimony whereof I affix my signature.
WALTER C. ANDERSON.
